(57) **CLAIM**

The ornamental design for an earbud cleaning kit, as shown and described.

DESCRIPTION

FIG. 1 is a perspective view of an earbud cleaning kit, which is comprised of a handle component; a cap component; and five attachable tip components, showing my new design.

FIG. 2 is an assembled perspective view of the earbud cleaning kit of FIG. 1, showing the handle and cap components attached to a first tip component;

FIG. 3 is a front elevational, exploded view of FIG. 2;

FIG. 4 is a rear elevational, exploded view of FIG. 2;

FIG. 5 is a right side elevational, exploded view of FIG. 2;

FIG. 6 is a left side elevational, exploded view of FIG. 2;

FIG. 7 is a top plan, exploded view of FIG. 2;

FIG. 8 is a bottom plan, exploded view of FIG. 2; and

FIG. 9 is a perspective, exploded view of FIG. 2.

FIG. 10 is an assembled perspective view of the earbud

cleaning kit of FIG. 1, showing the handle and cap components attached to a second tip component;

FIG. 11 is a front elevational, exploded view of FIG. 10;

FIG. 12 is a rear elevational, exploded view of FIG. 10;

FIG. 13 is a right side elevational, exploded view of FIG. 10;

FIG. 14 is a left side elevational, exploded view of FIG. 10;

FIG. 15 is a top plan, exploded view of FIG. 10;

FIG. 16 is a bottom plan, exploded view of FIG. 10; and

FIG. 17 is a perspective, exploded view of FIG. 10.

FIG. 18 is an assembled perspective view of the earbud

cleaning kit of FIG. 1, showing the handle and cap components attached to a third tip component;

FIG. 19 is a front elevational, exploded view of FIG. 18;

FIG. 20 is a rear elevational, exploded view of FIG. 18;

FIG. 21 is a right side elevational, exploded view of FIG. 18;

FIG. 22 is a left side elevational, exploded view of FIG. 18;

FIG. 23 is a top plan, exploded view of FIG. 18;

FIG. 24 is a bottom plan, exploded view of FIG. 18; and

(Continued)

FIG. 25 is a perspective, exploded view of FIG. 18. FIG. 26 is an assembled perspective view of the earbud cleaning kit of FIG. 1, showing the handle and cap components attached to a fourth tip component; FIG. 27 is a front elevational, exploded view of FIG. 26; FIG. 28 is a rear elevational, exploded view of FIG. 26; FIG. 29 is a right side elevational, exploded view of FIG. 26; FIG. 30 is a left side elevational, exploded view of FIG. 26; FIG. 31 is a top plan, exploded view of FIG. 26; FIG. 32 is a bottom plan, exploded view of FIG. 26; and FIG. 33 is a perspective, exploded view of FIG. 26. FIG. 34 is an assembled perspective view of the earbud cleaning kit of FIG. 1, showing the handle and cap components attached to a fifth tip component; FIG. 35 is a front elevational, exploded view of FIG. 34; FIG. 36 is a rear elevational, exploded view of FIG. 34; FIG. 37 is a right side elevational, exploded view of FIG. 34; FIG. 38 is a left side elevational, exploded view of FIG. 34; FIG. 39 is a top plan, exploded view of FIG. 34; FIG. 40 is a bottom plan, exploded view of FIG. 34; FIG. 41 is a perspective, exploded view of FIG. 34; and, FIG. 42 is an exploded perspective view of the earbud cleaning kit of FIG. 1, showing the handle and cap components.
